GALVANIZING MACHINE EXTRACTING
MECHANISMClifford E. Brownell, Buffalo, N. Y., assignor to
Lisk-Savoy Corporation, Buffalo, N. Y.Original application May 7, 1948, Serial No.
25,655. Divided and this application August 23,
1951, Serial No. 243,284

12 Claims. (Cl. 118—52)

1

This invention relates to machines for automatically galvanizing metallic receptacles and analogous objects and is a division of my prior-filed co-pending application Serial No. 25,655, now Patent No. 2,573,660, filed May 7, 1948.

Galvanizing sheet steel objects to protect them from corrosion is an ancient art and, as practiced commercially, comprises immersing the object in a bath of molten zinc through a floating layer of flux. The object is then moved in the zinc bath to another part thereof where the layer of flux is not present and is withdrawn.

The handling of the object in the molten zinc bath and the removal thereof from the bath is a process which requires considerable skill on the part of the workman due to the great weight of the zinc and its constant resistance to displacement and also because the object must be withdrawn from the bath and moved and rotated in various ways during its emergence and immediately thereafter to insure a uniform zinc coating. This handling and manipulation immediately after extraction from the bath also controls the surface appearance of the galvanized object, what is known in the art as "spangle."

Galvanizing steel receptacles is today practiced universally by hand, the workman depositing, manipulating and withdrawing the receptacles from the zinc bath by means of tongs. Several workmen usually handle each article in succession, one workman depositing the article in the bath, another moving it from the zone of the floating flux layer, and still another withdrawing it from the bath and manipulating it immediately thereafter. It is also necessary for one of these workmen or an additional one to skim the surface of the zinc bath immediately before the article is withdrawn to remove an oxide scum which continuously forms thereon and mars the work if the article is drawn therethrough in the withdrawing operation.

The labor problem is notoriously bad in the galvanizing industry. The objects are cleansed in an acid pickling bath just before they are introduced to the galvanizing bath. Accordingly, strong acid fumes are present which are but one of a number of objectionable factors. Secondly, the heat of the galvanizing bath is great and a number of workmen must be directly adjacent to the bath and partly over it. Third, the fumes of the molten zinc itself and of the sal ammoniac flux floating thereon contribute to the bad conditions. Besides all this, the physical strain of handling the receptacles in the bath and in re-

2

moving them from the bath is great and withall requires considerable skill and training.

Despite all this, and notwithstanding the extreme difficulty of keeping a galvanizing plant properly manned, no successful machinery for carrying on the galvanizing of sheet steel receptacles has evolved prior to the present invention.

The present invention provides a machine which automatically effects all of the receptacle handling operations from a time prior to immersion of the receptacle to a point where the receptacle is completely drained and has cooled sufficiently to prevent damage to the zinc coating by further handling. According to the present invention this automatic handling is carried on in a continuous manner so that a number of receptacles are in the process of being galvanized and handled automatically by the machine currently. That is, while the machine is in the actual process of immersing one receptacle one or more other receptacles will be passing through the molten zinc bath and a further receptacle will be being drained and deposited on a conveyor belt or the like at the delivery end of the machine.

The automatic galvanizing machine of the present invention is characterized by the fact that the handling of the receptacles is divided between three distinct sub-combinations of mechanical elements. The first of such sub-combinations, hereinafter generally referred to as the inserting mechanism, presents a receptacle to the zinc bath and deposits it partly therein without any of the machine parts of the sub-combination contacting the molten zinc.

The second of the sub-combinations handles the receptacles entirely beneath the surface of the zinc bath so that the zinc with which the receptacle handling means is constantly in contact is in a molten condition and has no opportunity to harden thereon and impede proper operation. This second subcombination, herein-after generally referred to as the rotating arm assembly, grasps the particular submerged receptacle beneath the surface of the zinc bath, moves it therethrough, and moves it upwardly out of the bath without itself moving above the surface of the bath. A third sub-combination of elements, hereinafter generally referred to as the extracting mechanism, grasps a partially withdrawn receptacle at its upper side so that the extracting mechanism, like the inserting mechanism, never comes in contact with the molten zinc bath.

In the form disclosed herein by way of ex-

ample, the entire article handling mechanism is portable and is provided with power operated elevating and lowering means so that it may be freely removed completely from the galvanizing bath. This facilitates cleaning the bath which is necessary periodically and is known in the art as drossing. Also, it facilitates adjusting the normally submerged clamps or changing them for others for handling receptacles of a different size. The complete severability of the automatic handling means also makes it convenient to use the bath for hand galvanizing, if desirable.

The foregoing is merely a general outline of the broad principles of operation of the machine which forms the subject of the present invention. For a full understanding of its mode of operation, a complete embodiment is illustrated in the accompanying drawings and described in detail in the following specification. It is to be understood that such embodiment is by way of example and merely to illustrate the underlying principles of the present invention.

The scope of the invention is not limited to the form shown by way of example nor otherwise than as defined in the appended claims. The machine shown in the drawings and described in the following specification is proportioned and designed for accomplishing the galvanizing of ordinary water buckets or pails, such as are commonly used in domestic housework, but the same principles may be applied to receptacles of other proportions and styles and to other objects which require similar handling in galvanizing.

In the drawings:

Fig. 1 is a general perspective view of one form of the article handling mechanism of the present invention, viewed generally from the front and shown dissociated from the galvanizing bath proper;

Fig. 2 is a view similar to Fig. 1, likewise viewed generally from the front of the mechanism but from the right-hand or delivery side thereof;

Fig. 3 is a view similar to Fig. 1, but with the buckets shown in Fig. 1 removed;

Fig. 4 is a general perspective view of the article handling mechanism taken from the rear;

Fig. 5 is a fragmentary side elevational view of the mechanism for introducing buckets to the machine, that is, the inserting mechanism;

Fig. 6 is a detailed perspective view of the outer end of the inserting mechanism of Fig. 5 viewed generally in plan;

Fig. 7 is a fragmentary elevational view showing a rocker arm which controls the operation of the inserting mechanism;

Fig. 8 is a fragmentary side elevational view showing the mechanism and the control means which are operative to move the buckets through the galvanizing bath to the removal zone, called herein the rotating arm assembly;

Fig. 9 is a fragmentary view of the mechanism of Fig. 8 as viewed as indicated by the line 9—9 of Fig. 8;

Fig. 10 is a fragmentary cross-sectional view on the line 10—10 of Fig. 8;

Fig. 11 is a fragmentary end view of one of the clamping devices for grasping the buckets within the molten zinc bath;

Fig. 12 is a fragmentary side elevational view showing the bucket extractor mechanism;

Fig. 13 is a view similar to Fig. 12 but with portions omitted for added clearness and with the mechanism in another position of operation;

Fig. 14 is a view similar to Fig. 12 with the parts in still another position of operation;

Fig. 15 is a fragmentary top plan view of the mechanism of Figs. 12 through 14, viewed as indicated by the line 15—15 of Fig. 12;

Fig. 16 is a longitudinal cross-sectional view through the main operating shaft of the extractor mechanism of Figs. 12 through 15;

Fig. 17 is a fragmentary partial cross-sectional view of the outer end bucket gripping portion of the bucket extractor mechanism viewed generally as in Figs. 12 through 14 but on a larger scale;

Fig. 18 is a cross-sectional view on the line 18—18 of Fig. 16;

Fig. 19 is a fragmentary end elevational view, partly in cross-section, showing means for elevating and lowering the major part of the article handling mechanism for bringing it into position with respect to a galvanizing bath;

Fig. 20 is a partial top plan view of the main drive mechanism of the machine;

Fig. 21 is a somewhat schematic side elevational view of the galvanizing bath of the machine of the present invention with the location of the rotating arm assembly of the article handling mechanism indicated schematically;

Fig. 22 is a schematic top plan view of the galvanizing bath, likewise with the location of the rotating arm assembly indicated schematically;

Fig. 23 is a schematic view of the clamp controlling air cylinder of the inserter mechanism showing the valve control means therefor; and

Fig. 24 is an elevational view, partly in cross-section, of the master valve for the air cylinder of Fig. 23.

Throughout the several figures of the drawings, like characters of reference denote like parts and the following description will deal, in order, with the three main components into which the machine naturally divides; namely, the mechanism for bringing the buckets to the bath, the mechanism for handling the buckets in the bath, and the mechanism for removing the buckets from the bath and properly draining them.

Bucket inserting mechanism

The bucket inserting mechanism is indicated generally at 30 in Figs. 1 through 4 and is shown in detail in Figs. 5 through 7. The bucket inserting mechanism is adapted to pick buckets from an elevated platform 31 and move them to the galvanizing bath where they are picked up by submerged bucket handling means, designated generally 32 in Fig. 5 and in Figs. 1 through 4 and described in detail under a succeeding heading. The buckets may be placed in proper introductory position on platform 31 by hand or may be fed automatically thereto by any suitable conveyor means.

The bucket introducing mechanism 30 is supported by a table 34, which will be discussed further later herein, by means of a bearing bracket 35. Referring to Figs. 1 and 5, an arm 37 has opposed trunnions 38 which bear at opposite sides in bracket 35 for rotative movement about a horizontal axis. A shaft 39 is journaled at its inner end in arm 37 for rotative movement about its own longitudinal axis and has a bevel pinion 40 fixed thereto adjacent to arm 37.

At its outer end shaft 39 has fixed thereto an offset arm 42 which rigidly supports a fixed clamp bar 43. A movable clamp 44 has an operating rod 45 slidable in arm 42 and an operating piston 46 movable in an air cylinder 47 secured to arm 42. Air connections 48 and 49 to the opposite ends of cylinder 47 control clamping and unclamping movements of clamp 44.

Considering the full line position of the parts in Fig. 5, the back end of arm 37 is pivotally engaged by a yoke 53 which is in turn pivotally secured, through the medium of a turnbuckle adjustment 54 to a crank 55 fixed to a supporting shaft 56 journaled in bearings 58 and 59 supported by table 34, all as clearly shown in plan in Fig. 20.

Referring to Fig. 20, the numeral 65 denotes the main drive motor of the machine which connects with a conventional speed reducing gear box 66 by means of a belt drive 67, both the motor and the gear box being disposed upon the table 34. The output shaft 68 of gear box 66 has a supporting bearing 69 and a sprocket 70 which is connected by means of a chain 71 to a sprocket 72 fixed to shaft 56.

For each rotation of shaft 56, crank 55 reciprocates yoke 53 and thus moves shaft 39 downwardly and upwardly between the full-line and dot-and-dash line positions of Fig. 5, shaft 39 pivoting about trunnions 38. When shaft 39 is in its upper limit position as shown in dot-and-dash lines in Fig. 5, the clamping mechanism 43, 44 faces rearwardly, as shown, to be in position to clamp over the upper and lower edges of a bucket on platform 31, the bucket being designated A in Fig. 5.

As yoke 53 moves rearwardly, shaft 39 moves from the upper to the lower full-line position of Fig. 5 and as it does so, bevel pinion 40 rotates in planetary fashion about a fixed bevel gear 75 which rotates shaft 39 on its own axis, it being journaled in arm 37 as heretofore described. Shaft 39 rotates through an angle of 180° in its movement from the upper limit position to the lower limit position, at which position the clamping mechanism faces downwardly and thus properly presents bucket A to the mechanism which handles the buckets in the galvanizing bath.

Referring to Fig. 7, a rocker arm 77 is fixed to one of the trunnions 38 of arm 37 and is shown in the position it occupies when shaft 39 is in its upper position. In this position, an adjusting screw 78 carried by one of the arms of rocker arm 77 is in engagement with the operating element of a pilot valve 79 which operates a master valve (to be described later herein) which connects the ports 48 and 49 of cylinder 47 in such manner as to move clamp element 44 to clamping position.

After shaft 39 has swung downwardly to the full-line position of Fig. 5, a second adjustable screw 82 carried by the other arm of rocker arm 77 operates a second pilot valve 80 which acts upon the master valve to reverse the application of air pressure to cylinder 47 and thus release clamp 44 immediately after the engagement of bucket A by the submerged bucket-handling mechanism 32.

Mechanism for handling buckets in the bath (rotating arm assembly)

The mechanism for receiving the buckets from the inserting mechanism and for passing them through the bath to the position where they are extracted therefrom is illustrated primarily in Figs. 8 through 11, in addition to the general views, Figs. 1 through 4.

Referring to Fig. 8 a main drive and supporting shaft for the bath mechanism is designated 90 and is journaled in bearings 91 and 92 fixed to an oblique plate 93 which is part of a bracket 94 fixed to table 34. The bearing means 91 include thrust means for retaining shaft 90 against displacement in an axial direction. Shaft 90 is

continuously rotated during operation of the machine by means which will now be described. Since the rotating arm assembly operated by and with shaft 90, and of which shaft 90 is a principal component, includes four bucket clamping stations, the speed of rotation of shaft 90 will be one-fourth that of shaft 56 of the drive mechanism, so that one of the four sets of clamping mechanisms associated with shaft 90 is presented in the bucket receiving position, as shown in Fig. 8 each time the shaft 39 of the inserting mechanism introduces a bucket thereto.

A countershaft 96 is journaled in bracket 94 for rotation parallel to shaft 90 and carries a helical gear 97 which is driven by a mating helical gear 98 fixed to drive shaft 56 of Figs. 8 and 20. Countershaft 96 and shaft 90 have sprockets 99 and 100, respectively, connected by a driving chain 101.

Fixed to the lower end of shaft 90 are four radiating pairs of spaced plates 103 which are notched as at 104 in Fig. 8 to provide relatively stationary clamp jaws. Between each pair of spaced plates 103 there is disposed a rod 105, the upper end of each rod 105 having longitudinal slide bearing in a sleeve 106 fixed to shaft 90 for rotation therewith.

The lower ends of the several rods 105 are divergent as shown and have plates 108 welded or otherwise fixed thereto. Plates 108 have screw and slot connection with clamping jaws 109, whereby the latter may be adjusted to suit buckets of various heights. Rods 105 are normally held in their upper clamping position by means of compression coil springs 112 which encircle the upper portion of each rod and bear at one end against sleeve 106 and at their other ends against outwardly projecting blocks 113 which are retained on rods 105 by means of nuts 114. Shaft 90 has bearing in bearing 92 through the medium of sleeve 106 which is primarily journaled in bearing 92.

Reference will now be had to the means for controlling the clamping and unclamping action of rods 105. By way of explanation, the presence of a bucket in Fig. 8 is for illustrative purposes only and may be confusing as, in fact, buckets are not present in the clamping mechanism at top dead center. The machine, in the present illustrative embodiment is timed so that arm 39 introduces a bucket to a clamping station of the rotating arm assembly 90, 105, etc. when a particular pair of clamps 104, 109 are about 10 to 15° past top dead center. It is, therefore, at this point that clamp 109 should move to a clamping position. Likewise, the extractor mechanism to be described later engages a bucket to remove it at a point about 10 to 15° before the clamps of the rotating arm assembly which are holding the bucket have reached top dead center. It is accordingly at this point that a particular rod 105 must operate to unclamp the bucket from the submerged rotating arm assembly.

Referring to Fig. 8, the numerals 120 and 121 designate a bracket assembly supported rigidly by bracket 94 and in turn supporting an air cylinder 122 having air connections 123 and 124 at its opposite ends. A slide bracket 126 is guided for longitudinal movement relative to the bracket portion 121 and includes a lug 127 for engagement successively against the several offset blocks 113 of rods 105. Blocks 113 comprise 90° sectors so that lug 127 will remain in engagement with a block 113 for a considerable angular extent if

it is moved to the position for engaging such block. Air cylinder 122 includes a piston 130 whose piston rod 131 is fixed to a part of slide bracket 126 to control its movements.

A pair of cams 134 and 135 are mounted upon shaft 96 and are angularly adjustable thereon by means of screws 138 which pass through arcuate slots in the cams and engage a block 139 fixed to shaft 96. Cam 134 engages a pilot valve 142 which acts upon a master valve to connect the passages 123 and 124 of air cylinder 122 so as to move lug 127 of slide bracket 126 against whichever of the blocks 113 is in a generally upper position. This releases clamp 109 at the proper moment for the bucket secured thereby to be engaged by the extractor mechanism, now from 10 to 15° before top dead center.

As the arm assembly 90, 105, etc. continues to rotate, lug 127 remains in engagement with block 113 to hold clamp 109 unclamped until the second cam 135 engages the operating element of a pilot valve 143 which reverses the connection of passages 123 and 124 of air cylinder 122 through the medium of the master valve and retracts lug 127, permitting spring 112 of the particular rod 105 to move clamp 109 to clamping position. Repeating, this occurs about 10 or 15° after the particular clamp has passed top dead center and shaft 39 has positioned a successive bucket for reception by clamps 104 and 109. It will be noted that the single air cylinder 122 and cam and pilot valve assembly therefor serves successively to act upon each of the four clamping assemblies of the rotating arm assembly.

Bucket extracting mechanism

Reference will now be had to the means for removing the buckets from the arm assembly which rotates in the bath. In this connection it is to be noted that the problem involves more than merely grasping the bucket and transferring it to a final delivery position.

From the time when the bucket begins to emerge from the molten zinc bath until it is deposited as a complete product it must be manipulated bodily and rotatively in a somewhat complex manner to properly drain the molten zinc from all parts of the bucket and to control the flow of zinc over the surface of the bucket, both inside and out, to produce not only a uniform thickness of coating but also what is known in the art as uniform and proper "spangle," the characteristic mottled appearance of galvanized ware.

In manual galvanizing, as now universally practiced, this operation is performed by a skilled workman. The quality of the galvanized product depends upon his skill in manipulating and timing the manipulation of the bucket while the molten zinc is draining therefrom and the remaining zinc coating is hardening thereon.

The construction of the extracting mechanism will now be described, reference being had particularly to Figs. 12 through 18. Referring to Figs. 12 and 15, the numeral 150 designates a bearing bracket fixed to table 34 and comprising a pair of parallel upstanding walls between which the extractor mechanism generally is pivotally supported.

As shown in Figs. 12, 15, and 16, a sleeve 151 has trunnions 152 which extend rotatably through the walls of bracket 150 and a rearwardly extending arm 153 is fixed to sleeve 151. A bifurcated link 155 pivotally engages the back end of arm 153 as at 156 and is pivoted at its

other end to the outer end of a crank 158 fixed to shaft 56 of the main drive means, see Fig. 20.

A shaft 160 has anti-friction bearing support in sleeve 151 as at 161 and 162 and has fixed thereto a bevel gear 163 having an extended hub or sleeve portion 164, all as clearly shown in Fig. 16. Shaft 160 is retained in sleeve 151 against axial displacement by means of a washer 165 and a nut 166. At its forward end sleeve 164 of bevel gear 163 has fixed therein a shaft 170 which has fixed to its outer end a transverse generally vertical pin 171. Note that shaft 160, bevel gear 163, shaft 170 and transverse pin 171 comprise a fixed unitary extractor arm structure rotatable in sleeve 151.

The lower end of pin 171 gives pivotal support to a bucket clamp block 174, a trunnion 175 fixed to block 174 being journaled in pin 171 as shown in Fig. 12. The bucket clamp means proper of the extractor mechanism is shown in detail in Fig. 17. Block 174 comprises a relatively fixed clamp block engageable at the outside of a bucket and a movable clamp plate 177 is engageable at the inside of the bucket as shown in the full-line position of Fig. 17.

A pair of parallel links 178 and 179 connect pivotally between clamp block 174 and clamp plate 177 to guide the latter from the full-line clamping position illustrated in Fig. 17 to the dot-and-dash line position where it is not only unclamped but is withdrawn from the interior of the bucket.

An operating lever 182 for the clamping mechanism is pivoted as at 183 to a bracket 184 which forms a part of clamp block 174 and lever 182 is pivotally connected at its lower end to a link 185 which connects pivotally with one of the link pivots of the movable clamp plate 177. Also supported by clamp block 174 is an air cylinder 188 having air pressure connections 189 and 190 at its opposite ends and an operating piston and piston rod 191 and 192, respectively, the latter having pin and slot connection at its outer end with operating lever 182 as indicated at 194. It is believed that the manner in which the application of fluid pressure to the opposite ends of cylinder 188 moves clamp plate 177 to and from clamping position is obvious from the foregoing.

It has been noted that the entire bucket clamping mechanism of the extractor is pivoted to the extractor arm generally by means of trunnion 175 of clamp block 174 being journaled in the lower end of the transverse pins 171 of the extractor arm. The mechanism which controls pivotal movement of the clamping mechanism relative to the extractor arm will now be described.

Referring to Fig. 14, a bell crank 200 is pivoted to the upper end of transverse pin 171 of the extractor arm as at 201 and one arm thereof is pivoted to a link 202 as at 203. The other end of link 202 is pivoted to clamp block 174 as at 204. The other arm of bell crank 200 is pivoted to one end of an adjustable link 205 as at 207 and the other end of link 206 is pivoted to a collar 208 as at 209. Collar 208 is slidable axially relative to the extractor arm, being fixed to an annular end flange 211 of a sleeve 212 which is mounted for free sliding movement on sleeve 164 of bevel gear 163, see Fig. 16.

From the foregoing it will be seen that outward or forward movement of collar 208 will rock bell crank 200 in a counterclockwise direction and, through link connection 202, rock the

clamping mechanism in a counterclockwise direction about trunnion 175. Inward or rearward movement of collar 208 will rock the clamping mechanism in a clockwise direction. The means for producing axial movement of collar 208 will now be described.

A disc 215 is fixed against the annular flange 211 of sleeve 212 by means of a collar 216, again referring to Fig. 16. Bevel gear 163 has a face cam formation 217 and cam 217 and disc 215 coact only when the extractor arm assembly is in the raised position illustrated in Fig. 14.

A compression coil spring 218 disposed about sleeve 164 of bevel gear 163 acts between collar 208 and a collar 220 fixed to sleeve 164 to urge the assembly comprising collar 208, sleeve 212 and disc 215 rearwardly, that is, to the right as viewed in Fig. 16, until the right hand or rear end of sleeve 212 abuts bevel gear 163, as there shown. Incidentally, the assembly including collar 208 is restrained against rotative movement relative to sleeve 164 by means of a screw 221, see Fig. 18, which engages a keyway 222 in sleeve 164.

Referring to Fig. 14, a slide 225 is supported for guided sliding movement between the upper portions of the walls of bracket 150 and carries a pair of rollers 226 and 227. When the extractor arm is in the raised position illustrated in Fig. 14, roller 226 is in position to be engaged by cam formation 217 of bevel gear 163 and roller 227, in turn, acts against disc 215 to impart counterclockwise movement to the extractor clamp assembly against the bias of spring 218.

A bevel gear 230 meshing with bevel gear 163 is mounted for free rotation on one of the trunnions 152 of sleeve 151. When bevel gear 230 is held against rotation and the extractor arm is raised or lowered by pivotal movement on trunnions 152 bevel gear 163 derives rotative movement by planetary rotation about bevel gear 230. Bevel gear 163 is desired to have further rotative movement by direct drive from bevel gear 230 and the means for rotating bevel gear 230 to produce such driving and for other purposes to be explained later will now be described.

Referring to Figs. 14 and 15, a line 234 is pivoted at its forward end to bevel gear 230 as at 235 and is provided with a cam follower 236 at its rear end. The rear portion of link 234 is constrained to a predetermined path of movement by a link 237 which is pivoted thereto as at 238 and to table 34 as at 239. Link 234 is normally urged rearwardly by an extension spring 240, one end of which is secured to a bracket 241 on link 234 and the other end of which is secured to a bracket 243 which is fixed to and extends rearwardly from bearing 59.

Movement of link 234 is controlled by a cam 245 fixed to drive shaft 56. The contour of cam 245 includes a low gradually falling portion of considerable extent during which link 234 moves rearwardly from the position illustrated in Fig. 12, and during this part of the operation bevel gear 230 is rotated in a clockwise direction. Following this on the cam 245 there is a relatively abrupt rise and fall which reciprocates link 234 forwardly and then rearwardly through a much greater distance than the initial movement referred to.

As shown in Fig. 12, one of the trunnions 152 of sleeve 151 has an arm 248 fixed thereto which, upon lowering movement of the extractor arm assembly to the position of Fig. 12, automatically engages a pilot valve 249 which actuates a mas-

ter valve to connect cylinder 188 for moving the clamp plate 177 to clamping position. A second pilot valve for reversing the connections to cylinder 188 to unclamp is associated with the inserting mechanism and operates simultaneously with the inserter unclamping pilot valve 80. Referring to Fig. 7, a pilot valve indicated by the numeral 250 is located directly behind pilot valve 80 as viewed in Fig. 7 and a second adjustable contact screw 251 is carried by a lateral extension 252 of rocker arm 77, screw 251 being directly behind screw 82 as viewed in Fig. 7. Pilot valve 250 and contact screw 251 therefor appear in Fig. 1.

A cycle of operation of the extractor mechanism will now be described, beginning with the position of the parts in Fig. 12 where the clamping mechanism has just operated, by movement of arm 248 to operate pilot valve 249, to engage a bucket presented thereto by the mechanism which supports the buckets in their movement through the galvanizing bath. The clamping mechanism in the bath is timed to release a bucket within a brief period after it has been engaged above the bath by the extractor clamp mechanism.

Beginning with Fig. 12, during the first 180° of movement of drive shaft 56, the extractor arm assembly, including sleeve 151, shafts 160 and 170 and their associated parts, move upward by reason of the operation of crank 156 and link 155 on arm 153 of sleeve 151. During the first 150° of this movement, there is a falling off of the profile of cam 245 so that link 234 moves to the right, as viewed in Fig. 12, and rotates gear 230 about 15° in a clockwise direction which, by reason of the gear ratio, tends to rotate bevel gear 163 in a clockwise direction as viewed from the front of the machine.

This movement of bevel gear 230 is provided merely to neutralize the tendency which gear 163 would otherwise have to rotate in a counterclockwise direction along bevel gear 230 by planetary action if bevel gear 230 were stationary. In other words, during this 150° of movement bevel gear 163 has no rotation about its own axis. The mechanism is arranged to operate in this manner because it is desired to lift the bucket out of the bath with no lateral or rotative movement.

Lateral movement during this period of continued emergence of the bucket from the bath would pick up scum from the surface of the bath and affect the quality of the work by marring the surface thereon.

During the last 30° of this first half revolution of drive shaft 56, cam 245 has a dwell and gear 230 is therefore held stationary. During this period bevel gear 163 rotates by planetary action against bevel gear 230 and this causes cam formation 217 to act against cam follower 226 to move the clamping mechanism quickly downwardly about trunnion 175, through cam follower 227, the intervening disc 215, collar 208, link 206, bell crank 200, and link 202, all in the manner previously described. This movement drains molten zinc from the recess at the outside of the bottom of the bucket, as shown in Fig. 14 and shakes drops from the edge thereof by reason of the abruptness of the movement.

During this same 30° period, the planetary rotation of bevel gear 163 rotates the clamping mechanism about the axis of bevel gear 163 in a counterclockwise direction to begin rotation of the bucket, the bucket then being again held with its bottom slightly higher than its top, approxi-

11

mately as indicated in Fig. 13, the cam formation 217 having by this time left follower 226, and the clamp mechanism having been restored to its initial position of inclination relative to trunnion 175 by operation of spring 218 against collar 208.

At the conclusion of the first 180° of rotation of drive shaft 56, the relatively large lobe formation of cam 245 has already begun to act upon follower 236 to rotate gear 230 in a counterclockwise direction as viewed in Figs. 12 through 14 through the operation of link 234. This augments the counterclockwise rotation of bevel gear 163 and the bucket is thus relatively rapidly revolved about the general axis of the extractor arm, and this rotation continues during approximately the first 90° of the second half of the rotation of drive shaft 56, or until the high point of the lobe of cam 245 is in contact with follower 236.

As shown in Figs. 12 through 14, the extractor clamp mechanism is offset rearwardly from the axis of the extractor arm as viewed in those figures. Referring to Fig. 1, the clamping mechanism is offset to the left of the axis of the extractor arm when the parts are in the beginning position illustrated in Fig. 12, as viewed from the front of the machine.

Rotation of the extractor arm beginning at about 150° through the cycle and continuing to about 270° through the cycle revolves the extractor clamping mechanism through approximately 180° about the axis of the extractor arm, so that at this point in the cycle the extractor clamp mechanism would be forwardly of the axis of the extractor arm assembly as viewed in Figs. 12 to 14 or to the right of that axis as viewed from the front of the machine. Also this revolution moves the parts so that the bucket is directly above the stationary clamp block 174, rather than below as in Figs. 12 through 14.

The bucket is thus in a position more to the right, as viewed from the front of the machine, than when it was engaged by the clamping mechanism. At this point the extractor clamp plate 177 releases by operation of air cylinder 188 and the bottom of the bucket drops downwardly, the outside wall thereof near the top of the bucket pivoting about the point on the clamp block marked 255 in Fig. 17; the clamping mechanism then being, of course, in an up-side-down position from that shown in Fig. 17, and the bucket thus drops to a vertical upright position upon a suitably located conveyor belt for ultimate delivery.

During the next 75° of operation of drive shaft 56, that is from about 270° to 345°, cam 245 returns toward initial position and the extractor arm is again lowered and rotated to approximately the initial position, spring 248 serving to draw the link 234 rearwardly and rotate gear 230 in a clockwise direction to cooperate with and augment the planetary action of gear 163 and thus revolve the clamping mechanism reversely through 180° to initial position. The profile of cam 245 during the last 15° of the cycle is such that it again neutralizes planetary action of gear 163 and the extractor arm drops straight down to pick up a succeeding bucket and repeat the extracting process.

General arrangement

The description thus far has referred to the galvanizing bath only in general terms. As illustrated in Figs. 1 through 4 the entire inserting, rotating and extracting mechanism is portably

12

mounted upon a frame 260, see Fig. 3, having casters 261, so that the article handling mechanism can be brought to a point adjacent the galvanizing bath and then moved into proper position relative thereto. Referring to Fig. 19, table 34 is hinged at its rear edge to a base plate 262 as at 263 and base plate 263 is provided with grooved wheels 264 which engage an inverted V-shaped track 265 at the rear edge of an upper frame portion 266 of the frame 260. Near its forward edge base plate 262 has plain wheels 268 for operation on the upper frame portion 266 of frame 260.

Air cylinders 270 are pivoted at their lower ends to the forward portion of table 34 at opposite ends thereof, and the piston rods 271 of air cylinders 270 are pivoted at their outer or lower ends to base plate 262 as at 272. Cylinder 270 has air connections 275 and 276 at its upper and lower ends, respectively, and these passages connect with a conventional three-way manual valve designated 278 in Fig. 4. Valve 274 may be moved from its illustrated neutral position to connect air pressure to either the upper or lower end of cylinder 270 and thus move its piston (not shown) in either direction therein.

It is believed that the operation of air cylinder 270 in raising table 34, and accordingly the entire article handling machine, from the full-line position of Fig. 19 to the dot-and-dash line position is obvious from the foregoing. When table 34 is raised to the dot-and-dash line position of Fig. 19 by operation of air cylinder 270, it may be held safely and securely therein by means of arms 280 pivoted at one end to table 34 and adapted to depend therefrom into supporting engagement upon base plate 262 as shown in Fig. 19.

In Figs. 21 and 22 the numeral 282 designates a steel tank adapted to contain molten zinc as at 283. A refractory jacket for the tank 282 is designated 284 and has openings 285 to expose portions of tank 282 for heating by means of gas jets 286. At the upper rear portion of the bath there is a plate 290 disposed at the same level as the upper frame portion 266 of frame 260 and provided with an inverted V-shaped rail 291.

Frame 260 is brought to the bath with tracks 265 and 291 in alignment and the article handling mechanism is rolled from frame 260 onto the plate 290. In Figs. 21 and 22 the numeral 293 designates a flux box which is open at its upper and lower sides and extends a short distance into the bath 283. Flux box 293 contains a layer of sal ammoniac flux which floats on the surface of the molten zinc within the flux box as at 294, and the inserter mechanism is positioned to dispose buckets into the bath through this flux blanket.

In Figs. 21 and 22 the approximate location of shaft 90 of the rotating arm assembly during galvanizing operation is indicated schematically. However, in order to avoid interference of parts in bringing the article handling mechanism into proper assembly with the galvanizing bath, the handling mechanism is initially moved to a position more to the right, as viewed in Fig. 22, than its final position. The table 34 is then lowered to project the clamps 164, 169, etc. into the bath as indicated in Fig. 8, and the article handling means is then moved somewhat to the left to bring shaft 90 into the approximate position indicated in Fig. 22.

In galvanizing generally, it is necessary to frequently skim the surface of the bath at the point where the article emerges therefrom, usually each time an article is to be extracted from the

tank. In using the apparatus of the present invention, this skimming may be effected manually between the emergence of successive articles. However, if desired, automatic skimming means may be incorporated without departing from the principles of the present invention.

Clamp control air cylinders

In describing the clamp control air cylinders of the inserter, the rotating arm assembly, and the extractor, those cylinders being designated 47, 122, and 188, respectively, reference was had to a pair of pilot valves, in each instance, for effecting clamping and unclamping operation of the air cylinders through the medium of a master control valve. The three master control valves are identical and may be located about the machine wherever convenient, the connections being the master control valves and the air cylinders being by means of flexible conduits.

In the present example air controlled master valves and pilot valves of the Ross Operating Valve Co. are used and these devices are familiar to those skilled in the automatic machine art. However, to render the present disclosure complete, the air control system of the inserter clamp mechanism will be set forth schematically. Since the pilot and master valve systems of the rotating arm assembly clamp mechanism and the extractor clamp mechanism are identical with that of the inserter, no further reference to those systems is necessary.

Referring to Fig. 24, a Ross pressure controlled master valve comprises a casing 300, the details of the interior passages thereof being shown only schematically in Fig. 23. The casing contains a pair of aligned normally closed poppet valves 301 and 302 and a pair of normally open poppet valves 303 and 304. A rocker arm 306 is normally biased to the counterclockwise position of Fig. 24 by the springs of valves 301 and 302.

A plunger 308 operating in a cylinder 309 in casing 300 is moved upwardly by pressure from the pilot valve system and when so moved an abutment 310 thereon engages the rocker arm 306 and rocks it in a clockwise direction whereupon the latter opens valves 301 and 302 and permits the lighter springs of valves 303 and 304 to move them to closed position. When pilot valve pressure against piston 308 ceases, the valves again assume the position illustrated in Figs. 23 and 24.

Referring to the general schematic view, Fig. 23, pressure from a compressed air supply designated 312 goes by way of conduit 313 to valves 302 and 303 and by way of conduit 314 to a lower chamber 315 (as viewed in Fig. 23) of pilot valve 79 of the inserter. This chamber is normally closed off from an upper chamber 317 of pilot valve by a valve 318 held closed by a relatively light spring 319.

An outlet conduit 320 from upper chamber 317 of pilot valve 79 connects with the lower chamber of pilot valve 80 of the inserter. The interior construction of pilot valve 80 is identical with the interior of pilot valve 79. Outlet conduit 320 also connects with cylinder 309. The upper chamber of pilot valve 80 exhausts freely to the atmosphere at 321.

Pilot valve 79 has a plunger 323 biased outwardly by a spring 324 for unseating valve 318 by inward movement of the plunger occasioned by engagement of screw 78 of rocker arm 77 therewith. Pilot valve 80 has a similar operating plunger 326 for unseating its valve (not shown).

In Fig. 23 the clamp operating cylinder of the inserter is indicated at 47 and its left-hand air connection 48, as viewed in Figs. 5 and 23, is connected, by means of a conduit 328, to a passage of the master valve designated 327 and extending between valve 301 and the side of valve 303 opposite to the air pressure connection 313. The other connection 49 of cylinder 47 is connected to valve 302, at the side opposite to the compressed air supply passage 313, by a passage 329. This same opposite side of valve 302 is connected to one side of valve 304 by a passage 330, and the other side of valve 304 is connected to the side of valve 301 opposite to passage 327 by a passage 331. The side of valve 301 opposite passage 327 is vented to the atmosphere as at 334.

With the valves in the position shown in Fig. 23 compressed air is applied to the left end of cylinder 47 by way of conduit 313, open valve 303, and passages 327 and 328, and piston 46 is accordingly in its right-hand unclamping position. At the same time the right end of cylinder 47 is vented to the atmosphere by way of conduit 329, passage 330, open valve 304, passage 331 and exhaust outlet 334. The movable clamp element 44 is thus held in its unclamped position.

Upon engagement of screws 78 of rocker arm 77, Fig. 7, against plunger 323 of pilot valve 79 in the upper position of shaft 39, valve 318 of pilot valve 79 is opened and spring 319 is inadequate to itself raise valve 318, in the absence of differential pressure thereagainst, to closed position when plunger 323 is released. Therefore, compressed air is connected through pilot valve 79 and conduit 320 to the master valve operating cylinder 309, and piston 308 thereof operates to reverse the valves 301 through 304.

Under these conditions compressed air flows through conduit 313, past open valve 302 (valve 303 being now closed), and through conduit 329 to the right-hand connection 49 of cylinder 47. At the same time left-hand connection 48 thereof is vented through conduit 328, past valve 301 which is now open, and through exhaust passage 334. Piston 46 is accordingly moved to the left to clamp a bucket.

Subsequently, when plunger 326 of pilot valve 80 is depressed by engagement of screw 82 thereagainst, after shaft 39 has swung down to deliver the bucket to the rotating arm assembly of the tank handling mechanism, line 329 is vented through pilot valve 80 and exhaust passage 321, valve 318 is closed by the differential pressure thereon assisted by spring 319, the absence of pressure in cylinder 309 causes piston 308 to lower and valves 301 and 302 again are closed and valves 303 and 304 are reopened. This repeats the condition illustrated in Fig. 23 and the exhaust clamp is again released.

What is claimed is:

1. Means for extracting buckets and analogous articles from a galvanizing bath comprising a support, an extractor arm pivoted at one end to said support and having bucket gripping means at its opposite end, said arm being rotatable about its longitudinal axis, said arm having a lower position for gripping the upper projecting rim portion of a bucket partly projecting from a galvanizing bath, means for pivoting said arm upwardly to raise the bucket from the bath and incline the same to drain the interior thereof, and means operable after the bucket has left the bath to rotate said arm about its own axis to rotate the bucket during hardening of the coating to produce uniform metal deposit and spangle,

2. Means for extracting buckets and analogous articles from a galvanizing bath comprising a support, an extractor arm pivoted at one end to said support and having bucket gripping means at its opposite end, said arm being rotatable about its longitudinal axis, said arm having a lower position for gripping the upper projecting rim portion of a bucket partly projecting from a galvanizing bath, means for pivoting said arm upwardly to raise the bucket from the bath and incline the same to drain the interior thereof, means operable subsequently for moving the bucket gripping means to lower the bottom of the bucket relative to the top to drain its under side, and means operable after the bucket has left the bath to rotate said arm about its own axis to rotate the bucket during hardening of the coating to produce uniform metal deposit and spangle.

3. Means for extracting buckets and analogous articles from a galvanizing bath comprising a support, an extractor arm pivoted at one end to said support and having bucket gripping means at its opposite end, said arm being rotatable about its longitudinal axis, said arm having a lower position for gripping the upper projecting rim portion of a bucket partly projecting from a galvanizing bath in approximately horizontal position, means for pivoting said arm upwardly to raise the bucket from the bath and incline the same to drain the interior thereof, and means operable after the bucket has left the bath to rotate said arm about its own axis to rotate the bucket during hardening of the coating to produce uniform metal deposit and spangle.

4. Means for extracting buckets and analogous articles from a galvanizing bath comprising a support, an extractor arm pivoted at one end to said support and having bucket gripping means at its opposite end, said arm being rotatable about its longitudinal axis, said arm having a lower position for gripping the upper projecting rim portion of a bucket partly projecting from a galvanizing bath, means for pivoting said arm upwardly to raise the bucket from the bath and incline the same to drain the interior thereof, and means operable after the bucket has left the bath to rotate said arm about its own axis to rotate the bucket during hardening of the coating to produce uniform metal deposit and spangle, said gripping means being offset relative to the arm axis whereby said rotation displaces the bucket laterally from its point of emergence from the bath for release at a delivery point.

5. Means for extracting buckets and analogous articles from a molten metal bath comprising a support, an extractor arm pivoted at one end to said support and having bucket gripping means at its opposite end, said arm being rotatable about its longitudinal axis, said arm having a lower position for gripping the upper projecting rim portion of a bucket partly projecting from a galvanizing bath, means for pivoting said arm upwardly to raise the bucket from the bath and incline the same to drain the interior thereof, and means operable after the bucket has left the bath to rotate said arm about its own axis to rotate the bucket during hardening of the coating to produce uniform metal deposit.

6. Means for extracting buckets and analogous articles from a galvanizing bath comprising a support including means for engaging a bucket after it has passed through said bath and is partly projected therefrom in approximately horizontal position, means mounting said support

70

for rotation and for upward and downward movement, said engaging means including means for gripping the bucket adjacent its rim at the then upper portion thereof, means for automatically moving said support means upwardly in a curved path to drain the interior of the bucket and means operable after the bucket has left the bath to rotate the support and thus rotate the bucket about an axis generally lengthwise thereof to produce uniform metal deposit and spangle.

7. Means for extracting buckets and analogous articles from a galvanizing bath comprising a support including means for engaging a bucket after it has passed through said bath and is partly projected therefrom in approximately horizontal position, means mounting said support for rotation and for upward and downward movement, said engaging means including means for gripping the bucket adjacent its rim at the then upper portion thereof, means for automatically moving said support means to raise the bucket and simultaneously raise the bottom thereof relative to the top to drain the interior of the bucket, and means operable after the bucket has left the bath to rotate the support and thus rotate the bucket about an axis generally lengthwise thereof to produce uniform metal deposit and spangle.

8. Means for extracting buckets and analogous articles from a galvanizing bath comprising a support including means for engaging a bucket after it has passed through said bath and is partly projected therefrom in approximately horizontal position, means mounting said support for rotation and for upward and downward movement, said engaging means including means for gripping the bucket adjacent its rim at the then upper portion thereof, means for automatically moving said support means to raise the bucket and simultaneously raise the bottom thereof relative to the top to drain the interior of the bucket, means operable subsequently to lower the bottom of the bucket relative to the top to drain its under side, and means operable after the bucket has left the bath to rotate the support and thus rotate the bucket about an axis generally lengthwise thereof to produce uniform metal deposit and spangle.

9. Means for extracting buckets and analogous articles from a galvanizing bath comprising a support including means for engaging a bucket after it has passed through said bath and a portion of its rim projects upwardly therefrom, means mounting said support for rotation and for upward and downward movement, said engaging means including means for gripping said projecting rim portion, means for automatically moving said support means upwardly in a curved path to drain the interior of the bucket, and means operable after the bucket has left the bath to rotate the support and thus rotate the bucket about an axis generally lengthwise thereof to produce uniform metal deposit and spangle.

10. Means for extracting buckets and analogous articles from a galvanizing bath comprising a support including means for engaging a bucket after it has passed through said bath and a portion of its rim projects upwardly therefrom, means mounting said support for rotation and for upward and downward movement, said engaging means including means for gripping said projecting rim portion, means for automatically moving said support means upwardly in a curved path to drain the interior of the bucket, means

operable subsequently to lower the bottom of the bucket relative to the top to drain the recess at its under side, and means operable after the bucket has left the bath to rotate the support and thus rotate the bucket about an axis generally lengthwise thereof to produce uniform metal deposit and spangle.

11. Means for extracting buckets and analogous articles from a galvanizing bath comprising a support including means for engaging a bucket after it has passed through said bath and is partly projected therefrom in approximately horizontal position, means mounting said support for rotation and for upward and downward movement, said engaging means including means for gripping the bucket adjacent its rim at the then upper portion thereof, means for automatically moving said support means upwardly and for simultaneously moving the same to raise the bottom of the bucket relative to the top to drain the interior of the bucket, and means operable after the bucket has left the bath to rotate the support and thus rotate the bucket about an axis generally lengthwise thereof to produce uniform metal deposit and spangle.

12. Means for extracting buckets and analogous articles from a galvanizing bath comprising a support including means for engaging a bucket after it has passed through said bath and is partly projected therefrom in approximately

20
25
30

horizontal position, means mounting said support for rotation and for upward and downward movement, said engaging means including means for gripping the bucket adjacent its rim at the then upper portion thereof, means for automatically moving said support means upwardly and for simultaneously moving the same to raise the bottom of the bucket relative to the top to drain the interior of the bucket and to move the bucket laterally to be released at a receiving point horizontally offset from the portion of the surface of the bath from which the bucket is extracted, and means operable after the bucket has left the bath to rotate the support and thus rotate the bucket about an axis generally lengthwise thereof to produce uniform metal deposit and spangle.
